UNITED STATES PATENT OFFICE.

HERBERT E. WALTZ, OF STOCKTON, CALIFORNIA.

WIRE-PULLING HEAD.

Application filed February 25, 1927. Serial No. 171,057.

This invention relates to electricians' appliances and particularly to a device to be used for pulling wires through conduits. In the electric wiring for modern buildings, 5 the wires must be fed through metal conduits which are frequently of considerable length, which are connected at intervals by couplings, and which are apt to have sharp bends therein. It is therefore frequently 10 quite a task to pull the wires through such conduits and with the appliances at present available it often happens that the wires pull loose from the appliance, and have to be fished for or pulled back and a fresh 15 start made.

The principal objects of my invention therefore are to provide a pulling attachment which may be readily connected to the end of a wire in such a manner that the 20 wire will be held firmly against slipping; one with which a considerable number of wires may be simultaneously connected up and pulled and one which will not tend to catch and jam at the conduit couplings or in 25 the bends thereof.

A further object of the invention is to produce a simple and inexpensive device and yet one which will be exceedingly effective for the purpose for which it is designed.

30 These objects I accomplish by means of such structure and relative arrangement of parts as will fully appear by a perusal of the following specification and claims.

In the drawings similar characters of reference indicate corresponding parts in the 35 several views:

Fig. 1 is a side elevation of my improved attachment as in process of being clamped to a number of wires.

40 Fig. 2 is a sectional elevation of the device with the parts in their clamping position.

Fig. 3 is an end elevation of the wire receiving element of the device.

Referring now more particularly to the 45 characters of reference on the device, the attachment comprises a pair of separable cylindrical members 1 and 2 substantially of the same diameter. The member 1 is provided with a centrally disposed threaded 50 stud 3 which projects therefrom at one end, the opposite end of said member being recessed or cupped as at 4. Surrounding the stud in concentric relation therewith is a plurality of holes 5 drilled through said 55 member and communicating with the cup 4 adjacent the rim thereof.

The member 2 is centrally tapped to screw onto the stud and is concave on its face adjacent the member 1 as at 6 to form a clamping edge 7 around its outer periphery. A 60 rounded bail 8 is attached to and projects from the opposite or outer end of the member 2, to enable a pulling wire or the like to be readily applied to the device.

In operation the wires 9 of the cables 10 to be pulled are bared at one end from their insulation covering for a certain distance so as to enable the bare wires to be projected through and beyond the holes 5, each such hole being of a sufficient size to take all 70 the wires of each cable. The ends of the wires beyond the member 1 are then bent outwardly as shown in Fig. 1, to a point outwardly of the plane of the clamping edge of the member 2. The latter is then screwed 75 down tight onto the stud 3 so that the wires will be engaged and clamped between the edge 7 and the adjacent surface of the member 1. The ends of the wires then protruding from between said members are then 80 hammered over so as to lie adjacent the member 1, the latter being of reduced diameter for the adjacent portion of its extent as shown at 11, so that the wires will not project outwardly of the normal diameter 85 of the device.

It will therefore be seen that any necessary pulling pressure may be applied to the device to pull the cables through a conduit without danger of the wires slipping from 90 position.

The length of the two parts of the head when coupled together is sufficiently small so that there is no danger of the device jamming in a bend of any sharpness liable 95 to be encountered in the conduit. The general shape of the device including the bail is that of a bullet, so that it will slip easily through a conduit and all edges are rounded so as to eliminate the possibility of the device being caught by the ends of the conduit at the couplings. With this device applied to a number of cables the latter if sufficiently stiff may also be pushed through a conduit with no probability of the ends of 105 the wires engaging the walls or ends of the conduit.

From the foregoing description it will be readily seen that I have produced such a device as substantially fulfills the objects of 110 the invention as set forth herein.

While this specification sets forth in de-

tail the present and preferred construction of the device, still in practice such deviations from such detail may be resorted to as do not form a departure from the spirit of the 5 invention, as defined by the appended claims.

Having thus described my invention what I claim as new and useful and desire to secure by Letters Patent is:

1. A wire pulling head comprising a member 10 having an orifice therethrough to receive a wire, a central threaded stud projecting from one end of said member, the orifice being to one side of the stud, and a tapped member to be screwed onto the stud to engage and clamp a wire against the first 15 named member.

2. A wire pulling head comprising a member having an orifice therethrough to receive a wire, a central threaded stud projecting 20 from one end of said member, the orifice being to one side of the stud, and a tapped

member to be screwed onto the stud, said tapped member at its inner end being concaved to form a peripheral clamping edge for sharp engagement with a wire bent outwardly from the adjacent end of the orifice. 25

3. A wire pulling head comprising a member having an orifice therethrough to receive a wire, and another member to be advanced toward the outer end of the first 30 member to engage and clamp a wire passed through the orifice and bent outwardly therefrom; said first member from and adjacent its outer end being of a lesser width than the second member to an extent sufficient to enable the outer end of the wire after being clamped to be bent to lie along the first member without projecting past the 35 plane of the periphery of the second member.

In testimony whereof I affix my signature. 40

HERBERT E. WALTZ.
